United States Patent Office

Des. 214,386
Patented June 10, 1969

214,386

GAME BOARD

Claire C. Perruccio, 308 Maple Ave., and Gloria-Jean Bogue, 290 Maple Ave., both of Hartford, Conn. 06114

Continuation-in-part of design application Ser. No. 7,112, May 15, 1967. This application May 17, 1968, Ser. No. 11,991

Term of patent 14 years

Int. Cl. D21—01

U.S. Cl. D34—5

FIG. 1 is a top plan view of the game board.
 FIG. 2 is a front side view of the game board.
 FIG. 3 is a rear side view of the game board.
 FIG. 4 is a left-hand side view of the game board.
 FIG. 5 is a right-hand view of the game board.
 FIG. 6 is a vertical section taken generally as indicated at 6—6 in FIG. 1.
 FIG. 7 is a vertical section taken generally as indicated at 7—7 in FIG. 1.

Conventional legible matter and symbols are shown in broken lines.

This application is a continuation-in-part of application Ser. No. D. 7,112, filed May 15, 1967, for a design for a game board, now abandoned.

We claim:

The ornamental design for a game board, as shown and described.
